DESIGN FOR A DRESS AND SLIP ENSEMBLE

Margaret Michelson, New York, N. Y.

Application December 16, 1938, Serial No. 81,808

Term of patent 3½ years

To all whom it may concern:

Be it known that I, Margaret Michelson, a citizen of the United States, residing at 525 Seventh Avenue, New York, in the county of New York and State of New York, have invented a new, original, and ornamental Design for a Dress and Slip Ensemble, of which the following is a specification, reference being had to the accompanying drawing, forming part thereof.

Fig. 1 is the front view of the dress and slip ensemble design.

Fig. 2 is the back view of the dress and slip ensemble design.

The characteristic feature of my design resides in the combination on the specific dress and slip ensemble disclosed of the specific, cartridge pleated, bow appliques arranged on the dress bodice and on the slip skirt as shown, said slip bows being visible through the transparent dress skirt.

I claim:

The ornamental design for a dress and slip ensemble, substantially as shown and described.

MARGARET MICHELSON.
